UNITED STATES PATENT OFFICE.

NATHAN W. FLETCHER, OF CHICAGO HEIGHTS, ILLINOIS, ASSIGNOR TO
TURBINE MOTOR TOOL COMPANY, OF CHICAGO, ILLINOIS, A CORPO-
RATION OF ILLINOIS.

PNEUMATIC TOOL.

No. 839,128.

Specification of Letters Patent.

Patented Dec. 25, 1906.

Application filed April 20, 1904. Serial No. 204,085.

To all whom it may concern:

Be it known that I, NATHAN W. FLETCHER, a citizen of the United States, residing at Chicago Heights, in the county of Cook and State of Illinois, have invented certain new and useful Improvements in Pneumatic Tools; and I do hereby declare that the following is a full, clear, and exact description thereof, reference being had to the accompanying drawings, and to the letters of reference marked thereon, which form a part of this specification.

This invention relates to portable machines for cutting, polishing, or grinding of that class which have a rotative or turbine motor and a supporting-block or base-plate adapted to rest and slide upon the surface of the work or object to be operated upon and which supports a rotative grinding, polishing, or cutting tool and the motor which drives the same.

The invention consists in the matters hereinafter described, and pointed out in the appended claims.

As shown in the accompanying drawings, Figure 1 is a view in side elevation of a grinding or polishing machine constructed in accordance with my invention. Fig. 2 is a plan view thereof. Fig. 3 is a sectional plan view taken upon the section-line 3-3 of Fig. 1. Fig. 4 is a detail section through the tool-carrying shaft of the machine, showing the same provided with cutters.

As illustrated in said drawings, A indicates a disk which constitutes the non-rotative member of a turbine-motor, and B indicates the rotative member or wheel of said motor, which is provided with an annularly-arranged series of blades or buckets b, and is mounted on a bearing or supporting spindle C, secured centrally in the disk A.

D indicates a base plate or block on which the motor is mounted and which is provided with a flat horizontal bottom surface and with two rigid uprights or supporting-stands D' D'',

The disk A is provided with a radially-extending lug or projection A', which is engaged with a horizontal pivot pin or stud E, secured in the upper end of the standard D', which is located adjacent to one of the end margins of the supporting-plate D. Said disk A is also provided at a point diametric-

ally opposite the lug A' with an extension or arm A'', which projects radially from the side margin of the body portion and extends at one side of and is adapted to be adjustably secured to the standard D'', which latter standard is located near the opposite end of said block. The arm A'' is shown as forming an endwise extension of a radial rib A''' on the disk A. A passage a, extending through the said rib and arm, forms part of the passage by which air is supplied to the motor.

Attached to the disk A and projecting from the same beyond the pivot-stud E is an arm I, in which is mounted a horizontal tool-carrying shaft G. The disk A and arm I together constitute a rigid frame which carries the motor and the tool-carrying shaft G and which is pivotally connected with the plate by the pivot-stud E, which is located between the said shaft and the motor in such manner that the said shaft and the motor are adapted to move or swing vertically.

The standard D'' is provided with a slot d, arranged concentrically with the pivot pin or stud E, and a clamping-screw F passes through the curved slot d and engages the arm A'' on the disk A, said arm being preferably provided with a depending lug a', having a screw-threaded aperture which is engaged by the end of said clamping-screw, which latter is provided with a milled head f for turning the same. The rigid frame formed by the disk A and arm I is thus adapted to swing on the pivot-stud E in such manner that the tool-shaft G may be raised and lowered relatively to the base-plate D, while the clamping-screw F is adapted to clamp the arm A'' to the standard D'' and to rigidly hold the said frame in any position in which it may be placed or adjusted.

The tool-shaft G is shown as arranged parallel with the axis of rotation of the motor and as provided with a grinding-disk H, although it may carry any other kind of a rotative grinding, cutting, or polishing tool. Said shaft is mounted in bearings I' I'' on the outer end of the arm I and projects beyond or overhangs the adjacent end of the plate D. Inasmuch as the frame formed by the disk A and the arm I is pivoted to the base-plate at a point between the said tool-shaft and the axis of rotation of the motor, when the arm A'' is adjusted vertically on the

standard D² the tool-shaft and tool thereon will be correspondingly raised or lowered relatively to the said plate D. By thus mounting the parts on the plate D the frame carrying the motor and tool-shaft, provision is made for exact adjustment of the position of the tool carried by said shaft with respect to the surface of the work or object on which the plate D rests, while the motor is brought between the standards and in a nearly central position over said plate.

In the particular construction shown the supporting-arm I is widened horizontally at its outer end and is provided with laterally-separated arms which carry the two bearings I' I² for the shaft G. Provision is made for driving the said shaft from the motor, consisting of a belt-pulley B' on the rotative part or wheel B of the motor and a corresponding belt-pulley J, attached to the shaft G, said belt-pulley J in the particular construction shown being mounted on the end of the shaft G outside of the bearings I' and I². In the instance illustrated, moreover, the grinding-wheel H is attached to that end of the shaft which bears the pulley G outside of the said pulley, this construction bringing the grinding-wheel laterally beyond or outside of the adjacent side margin of the base-plate B and also outside of the belt-pulley B' of the motor, which projects in the instance shown beyond said side edge of the base-plate. This construction is employed in order that the grinding-wheel may be moved along the surface upon which the base-plate rests closely adjacent to a raised flange or other elevated part projecting upwardly from said surface.

To provide a strong and rigid connection between the arm I and the disk A, said arm is widened at its inner end and arranged to overlap the said disk A in its part adjacent to the pivot-stud E, said arm having an opening or aperture i, through which projects said stud and the lug A' on the disk A. Said lug is made of considerable lateral width and arranged to project from the rear face of said disk A, so that it has a long bearing on the stud E, and will thereby afford a firm and rigid connection between the motor-carrying frame and the supporting-plate.

In order that a close fit or bearing between the lug A' and the pivot-stud E may be always maintained, notwithstanding wear of the parts, said lug A' is, as herein shown, provided with a longitudinal slit extending inwardly from the outer end of the lug to the bearing-aperture, and a clamping-bolt a² is provided by which the parts on opposite sides of the slit may be drawn together to tighten the bearing about the pivot-stud.

The shaft G and its bearings I' I² are shown as adapted for taking up any wear that may take place in the use of the tool, said shaft for this purpose being provided

with two cones or conical enlargements g g' and the bearings I' I² having screw-threaded sleeves i' i², which enter screw-threaded apertures in the said bearings and are provided with internal conical bearing-surfaces which engage the said bearing-cones g g' on said shaft G. Said shaft G may be provided with any form of rotative grinding, cutting, or polishing tools. Preferably the shaft will be made square between the bearings I' I², as shown in the drawings, and will have opposite flat faces, to which may be secured cutters K K, as shown in Fig. 4, such as may be used for dressing or planing the surfaces of wood panels or the like. When the shaft is thus made square between the bearings I' I², the latter will have the form of split bearings or be provided with caps which may be removed to enable the shaft to be taken laterally from the bearings, as shown in the drawings.

The tool illustrated is provided with two handles L and M, which may be grasped when handling the same. The handle L is shown as made hollow and attached to the outer end of the arm A² and adapted for connection at its outer end with a supply-pipe. The handle M is shown as attached to the upper surface of the arm I, which carries the rotative tool-shaft.

For facilitating the exact adjustment of the tool-shaft with respect to the base-plate D, I have provided an adjusting-screw N, which engages an arm n on the standard D² and bears upwardly against an opposing surface of the arm A², which, as herein shown, is formed on the lower edge of the depending lug a'. Said adjusting-screw N is preferably provided with a milled head n', by which it may be readily turned by hand. In the use of said adjusting-screw N the clamping-screw is first turned to loosen the arm A² from its close or binding contact with the arm D² and the screw N then turned to bring the tool exactly into the desired position or relation to the bottom surface of the supporting-plate D. When the frame is moved to the desired position, the clamping-screw F is again tightened to firmly hold the said arm A² against the standard.

It will be understood from the above that the disk A, on which the operative parts of the motor are mounted, together with the arm I, attached thereto, constitute a rigid frame which carries the motor, the tool-carrying shaft, and the means for driving the said shaft from the motor, which frame is pivoted to the base-plate D by the pivot-stud E, so that said frame, together with the motor and the tool, may be moved or shifted in effecting vertical adjustment of the tool with respect to the work. The particular construction described by which the plate I is made in a separate piece from the body A of the motor is only one of many possible

constructions that may be employed to provide the necessary rigid frame for carrying the motor and tool-shaft, and I do not, therefore, desire to be limited to a frame made in the particular manner shown. It will be further understood that the disk A, which in the machine shown in the drawings constitutes the non-rotative part of the motor, need not necessarily constitute any portion of the motor itself, it being obvious that a machine embodying the general features of my invention may embrace a rotative motor of other form than the particular one illustrated in the drawings. The parts of the said motor 15 illustrated in the drawings correspond, so far as they are illustrated in the accompanying drawings, with the motor described and claimed in a separate application for Letters Patent filed by me April 27, 1904, Serial No. 20 205,098; but the features of construction in said motor constitute no part of the present invention.

I claim as my invention—

1. A pneumatic tool comprising a base-plate, having a flat, bottom bearing-surface, 25 a motor embracing rotative and non-rotative parts, a rigid frame of which the non-rotative part of the motor constitutes a part and which is provided with a rigid arm extending outside of the base-plate, a rotative tool-shaft driven by the motor, said tool-shaft being mounted in the arm of the rigid frame exterior to the base-plate, said frame being pivoted to the said base-plate with its 30 pivotal axis parallel with the bearing-surface of the plate, and in a manner affording adjustment of the tool-shaft toward and from the plane of the said bearing-surface, and means for adjustably securing said frame 35 from movement on the base-plate.

2. The combination with a base-plate provided with two standards, of a motor, a rotative tool-shaft which is driven from the motor, a rigid frame on which said motor and shaft are mounted, said frame being pivoted to one of said standards at a point between the tool-shaft and the axis of rotation of the motor, and means for adjustably securing said frame to the other standard.

3. The combination with a base-plate provided with two standards, a motor, a rotative tool-shaft driven from the motor, a rigid frame on which said motor and shaft are mounted, said frame having pivotal connection with one of said standards at a point between the central axes of the motor and the tool-shaft, the other standard being provided with a curved slot concentric with the pivotal axis of the frame, clamping means engaging 55 said slot for adjustably securing said frame to the said second standard.

4. The combination with a base-plate provided with two standards, a motor, a rotative tool-shaft driven from the motor, a rigid frame on which said motor and shaft are

mounted, said frame having pivotal connection with one of said standards at a point between the central axes of the motor and the shaft, the other standard being provided with a curved slot concentric with the pivotal axis of the frame, clamping means engaging said slot for adjustably securing said frame to the said second standard, and an adjusting-screw engaging the base-plate and acting on the frame for effecting adjustment 75 of the same.

5. The combination with a base-plate having a flat, bottom bearing-surface, and provided with two rigid standards which rise from the upper surface thereof, of a motor 80 embracing rotative and non-rotative parts arranged with the axis of rotation of the rotative part horizontal, a rigid frame of which the non-rotative part of the motor constitutes a part, and which is provided with a rigid arm extending outside of the base-plate, and in which said tool-shaft is mounted, said frame being pivoted to one of said standards, a horizontal tool-shaft mounted in said arm of the rigid frame exterior to the 85 base-plate, means for transmitting rotary motion from said motor to said tool-shaft, and means for adjustably securing said frame to the other of said standards.

6. The combination with a base-plate 90 provided with two standards located near opposite ends of said plate, a motor arranged with its axis of rotation horizontal, a horizontal tool-shaft which is driven from said motor, a rigid frame on which said motor and shaft 95 are mounted, said frame being connected with one of said standards by a horizontal pivot; the motor being located between the two standards and the tool-shaft exterior thereto, and means for adjustably securing 100 said frame to the second standard.

7. The combination with a base-plate, a motor, a rotative tool-shaft and a rigid frame on which said tool and motor are mounted, said frame being pivotally and adjustably 110 connected with the base-plate, and means affording vertical adjustment of the tool with respect to the base-plate, and said motor embracing a non-rotative part which constitutes a portion of said rigid frame.

8. The combination with a base-plate provided with two standards, a motor, a rotative tool-shaft, a rigid frame on which said motor and tool are mounted, said frame being pivoted to one of the said standards between the tool-shaft and the axis of rotation of the motor, and said motor embracing a 120 non-rotative part provided with a laterally-projecting arm which engages the other standard, and means for adjustably securing 125 said arm to the latter standard.

9. The combination with a base-plate, a motor arranged with its axis of rotation horizontal, a rotative tool-shaft, a rigid frame on which said motor and shaft are mounted, said

- frame being connected with the base-plate by a horizontal pivot located between the axis of rotation of the motor and the said tool-shaft, means for rigidly securing said frame to the base-plate, and means for transmitting motion from the motor to said shaft embracing belt-pulleys on the rotative part of the motor and the shaft, and a driving-belt trained over said belt-pulleys.
10. The combination with a base-plate, a motor arranged with its axis of rotation horizontal, a horizontal, rotative tool-shaft, a rigid frame on which said motor and said shaft are mounted, said frame being pivotally connected with the base-plate, and
- 15

means for adjustably securing the said frame to the base-plate; the end of said frame which carries the said tool-shaft being extended beyond one end of the base-plate and provided with two separated bearings for the 20 said tool-shaft.

In testimony that I claim the foregoing as my invention I affix my signature, in presence of two witnesses, this 13th day of April, A. D. 1904.

NATHAN W. FLETCHER.
